UNITED STATES PATENT OFFICE.

HUGH S. BRADY, OF WHEELING, WEST VIRGINIA, ASSIGNOR TO HAZEL-ATLAS GLASS COMPANY, OF WHEELING, WEST VIRGINIA, A CORPORATION OF WEST VIRGINIA.

CLOSURE FOR RECEPTACLES.

Application filed January 18, 1924. Serial No. 686,977.

To all whom it may concern:

Be it known that I, HUGH S. BRADY, a citizen of the United States, residing at Wheeling, Ohio County, West Virginia, 5 have invented a new and useful Improvement in Closures for Receptacles, of which the following is a specification, reference being had to the accompanying drawings, in which—

10 Fig. 1 is a section of a jar showing a closure embodying my invention in the mouth thereof; Fig. 2 is an enlarged section showing the position of the closure after the jar has been vacuumized or the 15 closure otherwise applied; and Figs. 3 and 4 are sections showing the application of my invention to a cap with a crimped on band and to a screw cap, respectively.

My invention relates to the sealing of 20 jars, tumblers, bottles and other receptacles, by applying thereto caps or covers and gaskets, which are held in position by atmospheric pressure. My invention in particular comprises a gasket applied on a seat 25 within the mouth of the receptacle and a cover or cap having a bearing against the inner surface of the gasket and extending upwardly and outwardly over the gasket to substantially the periphery of the receptacle. When the cover has been applied, 30 the atmospheric pressure upon the central portion of the cover, which has a dome-shaped or raised surface, forces the cover against the inner surface of the gasket, 35 wedging it tightly against the seat in the mouth of the receptacle, thereby forming an effective seal. My invention also comprises the various features which I shall hereinafter describe and claim.

40 Referring to the drawings, 2 indicates a receptacle, preferably of glass or similar material, having within its mouth a recess or seat 3, the face 4 of which has a slight draft to facilitate application and removal 45 of the closure. Arranged in the seat 3 is a rubber gasket 6, preferably of rectangular shape. The cover or lid has a dome-shaped or raised central portion 7, the normal diameter of which is preferably slightly 50 greater than that of the inner peripheral surface of the receptacle immediately below the recess or seat 3. Extending upwardly from the periphery of the central portion 7 of the cover at an abrupt angle is an an-

nular flange 8, which bears against the inner face 9 of the gasket 6. From the upper edge of the flange 8 a peripheral lip 10 extends outwardly so that its outer edge is approximately flush with the periphery of the receptacle. The outer edge of the lip 60 10 may, if desired, be formed in a bead 11 to eliminate the raw edge and reinforce the cover.

In applying the closure to the receptacle the gasket 6 may be placed in the recess 3 65 or upon the outer face of the flange 8 of the cover, and the cover is then placed in the position shown in Fig. 1. The receptacle 2 may then be vacuumized and the atmospheric pressure will draw down the dome-shaped or raised central portion 7 of the cover, which will cause the enlargement of 70 the diameter of such portion and force the flange 8 of the cover against the lower portion of the face 9 of the gasket, and the 75 lower portion of the gasket tightly against the lower portion of the face 4 of the recess 3, thus causing an effective sealing of the cover against the gasket 6, and the gasket against the surface 4 of the recess. The intersection 12 of the central portion 7 and the flange 8 of the cover is the 80 point at which the greatest expansion of the cover occurs, by reason of the enlargement of the diameter of the cover thereat as 85 a result of the depression of the central portion 7 of the cover, as is shown in Fig. 2, in which the arrow indicates the component of force. It follows that those 90 portions of the gasket 6 which lie nearest such intersection will be subjected to the greatest amount of pressure, with the result that such pressure will tend to cause the gasket to assume the shape of the wedge as is 95 shown in Fig. 2, in which the angle between the central portion of the cover and its flange tends to become more acute.

When the cover has been applied a slight space is preferably left between the lip 10 and the top surface 13 of the receptacle, so 100 as to permit the insertion of a tool, and thereby provide for ready breaking of the seal and the easy removal of the closure.

In Fig. 3 I have shown my invention applied to a cover 15 having a crimped on band 16 which engages the lip 17 of the cover and the shoulder 18 on the exterior of the receptacle. The band 16 assists in holding the 105

cover 15 in position when it has been applied and in maintaining intact the seal between cover, gasket 19 and receptacle.

In Fig. 4 I have shown my invention applied to a jar intended for a screw top 20. As the screw top 20 when applied presses the upper lip 21 of the sealing cover 22 down on the top surface of the gasket 23, it will increase the pressure upon the gasket 10 and thus render the seal between cover, gasket and receptacle more effective.

Closures embodying my invention may also be applied without vacuumizing to receptacles with hot contents, since the cooling off of the hot contents of the receptacle will reduce the pressure within the receptacle to a sufficient extent to enable the normal atmospheric pressure on the exterior of the closure to press down the dome-shaped 20 or raised central portion 7 of the cover and force the flange 8 outwardly against the gasket, and the gasket against the seat 3, and thereby effectively seal the receptacle.

The terms and expressions which I have employed are used as terms of description and not of limitation, and I have no intention, in the use of such terms and expressions, of excluding any mechanical equivalents of the features shown and described, 30 or portions thereof, but recognize that various structural modifications are possible within the scope of the invention claimed.

What I claim is:

1. In a closure for receptacles, a receptacle having a mouth; a flexible metallic cover having a dome-shaped central portion and an upturned flange extending upwardly from the periphery of the central portion; a gasket seating on the outer face of said flange in the region of the juncture between the central portion and flange and engaging the receptacle within its mouth; the central portion being arranged upon the application of external pressure to expand its peripheral 5 portion and thereby force the gasket firmly against the receptacle.
2. In a closure for receptacles, a receptacle having a mouth; a flexible metallic cover having a dome-shaped central portion; an upturned flange extending upwardly from the periphery of the central-

portion; a gasket engaging the exterior of said flange in the region of the juncture of said central portion and flange and having a bearing in said mouth; an annular lip 55 forming part of said cover projecting outwardly from said flange covering the gasket and the upper edge of the receptacle and acting as a retainer for the gasket; the central portion being adapted to be depressed 60 by atmospheric pressure to increase the diameter of said central portion and force the flange against said gasket and the gasket against the receptacle.

3. In a closure for receptacles, a receptacle having a mouth; a flexible metallic cover having a dome-shaped central portion and a flange acutely angled with regard to the central portion and extending upwardly from the periphery thereof; a gasket 70 engaging the exterior of said flange in the region of the juncture of said central portion and flange and having a bearing in said mouth; the central portion being arranged to be depressed by atmospheric pressure and 75 to exert through the flange a pressure on the gasket and deform it into wedge shape in cross-section; the angle between the central portion of the cover and its flange tending to become less acute as the pressure 80 is applied.

4. In a closure for receptacles, a receptacle having a mouth; a flexible metallic cover having a dome-shaped central portion and an upturned annular flange extending 85 upwardly from the periphery of the central portion; a gasket seating in said mouth and bearing on the outer face of said flange in the region of the juncture between the central portion and flange; the cover also having a lip extending radially from said flange 90 forming a reinforcement for the cover and a retainer for the gasket; the central portion being arranged to be depressed by atmospheric pressure and to exert through the flange a pressure on the gasket to effect sealing of the receptacle; and a supplementary holding member having a bearing 95 on the lip of the cover and on a projecting portion on the exterior of the receptacle. 100

HUGH S. BRADY.
